CLAIM

The ornamental design for a toiletry bag, as shown and described.

DESCRIPTION

FIG. 1 is a perspective view of a toiletry bag showing my new design where the toiletry bag is in a first configuration of use;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the toiletry bag where the toiletry bag is in a second configuration of use; and,

FIG. 10 is a perspective view of the toiletry bag where the toiletry bag is in a closed state.

The short thick evenly spaced broken lines in the drawings depict stitching and form no part of the claimed design. The long thin evenly spaced broken lines in the drawings depict portions of toiletry bag and form no part of the claimed design.
